ABRAHAM HAVENS, OF TRENTON, NEW JERSEY.

Letters Patent No. 89,761, dated May 4, 1869.

IMPROVED WASHING-MACHINE.

The Schedule referred to in these Letters Patent and making part of the same.

To all whom it may concern:

Be it known that I, ABRAHAM HAVENS, of Trenton, Mercer county, New Jersey, have invented an Improvement in Washing-Machines; and I do hereby declare the following to be a full, clear, and exact description of the same.

My invention consists in the combination, with an elastic rubbing-bed, having V-shaped ribs and grooves, of a number of rollers hung to a vibrating frame, and so constructed and arranged with respect to each other, and to the grooves of the rubbing-bed, that articles of clothing, &c., placed upon the latter, shall be moved from side to side, and submitted to a rubbing-action, similar to that of the hands upon an ordinary wash-board, all of which is fully described hereafter.

In order to enable others to make and use my invention, I will now proceed to describe its construction and operation, reference being had to the accompanying drawing, which forms a part of this specification, and in which—

Figure 1 is a longitudinal section of my improved washing-machine;

Figure 2, a sectional plan view of the same on the line 1-2, fig. 1;

Figure 3, a transverse vertical section on the line 3-4, fig. 1; and

Figure 4, a perspective view of part of the rubbing-bed, detached from the machine.

Similar letters refer to similar parts throughout the several views.

The box-shaped body A of the machine, which is supported upon legs a a, is open at the top, and has, at one end, a cock, b, through which suds or water may be drawn off when the machine is to be cleansed, &c.

A frame, B, consisting of arms c c, connected together by cross-pieces f, is hinged to and arranged to turn freely on projections e, at one end of the box A, and a similar frame, C, consisting of side-pieces h, braced together by rods i, is jointed to the upper end of the frame B, so as to turn freely thereon, as plainly seen in fig. 1.

Three spindles, k, k', and k'', are arranged to turn in the lower ends of the opposite side-pieces h of the frame C, and to each of these spindles is hung a number of double-cone-shaped rollers, F, of India rubber, or equivalent elastic material, these rollers being detachable separately from the spindles, to which they are secured by nuts or otherwise, and the rollers of one spindle being arranged with respect to those of the next, as best observed in fig. 2.

A rocking, or vibrating motion, upon a rubbing-bed, H, placed in the bottom of the box A, is imparted to the frame C and its rollers, by means of a crank-spindle, I, which turns in suitable bearings at the opposite sides of the box A, and with which the said frame is connected by means of a rod, l.

The rubbing-bed H above mentioned (shown detached from the machine in fig. 4) consists of a wooden frame, m, to the curved upper surface of which is secured the bed proper, of rubber or other suitable yield-

ing material, a series of V-shaped grooves and ribs being formed upon the said bed in the direction of its length, as best observed in figs. 2 and 4.

The V-shaped edges of the rollers F of the spindles k, k', and k'', enter and travel in the grooves of the rubbing-bed when the frame C is vibrated, the rollers of the spindles k and k' entering the grooves marked p, while those of the spindle k'' enter the intermediate grooves p'. (See figs. 2 and 3.)

The box A having been partly filled with soap-suds, the articles to be washed are placed upon the grooved and ribbed surface of the rubbing-bed, a vibrating motion upon the latter being then imparted to the frame C and its rollers, by means of the crank-spindle I.

When the frame is moved in the direction of the arrow, figs. 1 and 2, the rollers of the spindle k will first press the articles to be washed into the grooves p of the bed, from which they will be withdrawn, and forced into the grooves p' by the roller of the second spindle, k', the roller of the third spindle again pressing the articles into the grooves p.

On the reversal of the motion of the frame and its rollers, the same operation is repeated, each line of rollers exerting a pressure into its own set of grooves.

The effect of this alternate action of the rollers upon the clothes or other articles, is to move them from side to side upon the bed, and thus submit them to a rubbing-action upon the ribs of the same, similar to that of the hands upon an ordinary wash-board.

In addition to the longitudinal grooves, transverse grooves, arranged at suitable distances apart, may also be formed upon the rubbing-bed, for the purpose of affording a more perfect circulation of the soap-suds, without departing from my invention.

It will be seen that, owing to the manner in which the frames B and C are hung, the frame C, with its rollers, may be elevated so as to pass over any thickness of material without the action of the rollers, imparted by the crank-shaft, being interfered with, while, on tilting back the frame B, the frame C and its rollers will be entirely withdrawn from the box, so as to permit the withdrawal or insertion of the clothes.

It will also be seen that, as the conical rollers are separately detachable from their spindles, they may be separately removed as they become worn or injured, thus avoiding the great waste which ensues when all the rollers on each shaft are in one piece.

I claim as my invention, and desire to secure by Letters Patent—

The combination of the frame B, hung to the box A, and the frame C, hung to the upper end of the frame B, and carrying a series of conical elastic rollers, which may be detached separately from the shafts, for the purpose specified.

In testimony whereof, I have signed my name to this specification, in the presence of two subscribing witnesses.

ABM. HAVENS.

Witnesses:

JOHN WHITE,
C. B. PRICE.
